UNITED STATES PATENT OFFICE.

JAMES G. DAVIS, OF BUFFALO, NEW YORK.

FLOOR AND CEILING CONSTRUCTION.

1,347,146.

Specification of Letters Patent.

Patented July 20, 1920.

Application filed November 7, 1918. Serial No. 261,529.

To all whom it may concern:

Be it known that I, JOHN G. DAVIS, a citizen of the United States, residing in Buffalo, in the county of Erie and State of New York, have invented new and useful Improvements in Floor and Ceiling Constructions, of which the following is a specification.

This invention relates to a floor and ceiling construction having a plurality of body sections arranged adjacent to each other and forming channels between them, reinforcing bars or rods arranged in said channels, and a mass of coalescent material, such as concrete extending over said body sections and the channels between the same and embedding said reinforcing bars.

The objects of this invention are to provide a floor and ceiling construction of this character having means for more securely locking together the concrete mass and the porous body sections so that the latter will be more reliably supported by the former; also to provide efficient means for preventing the porous body sections from unduly abstracting the moisture from the mass of concrete and weakening the same before it becomes set; and also to provide superior means for supporting these reinforcing bars preparatory to being embedded in the concrete mass.

In the accompanying drawings:

Figure 1 is a fragmentary perspective view showing part of a completed floor and ceiling construction embodying my invention and another portion which is in the course of erection. Fig. 2 is a perspective view of one of the lower body sections of the floor and ceiling construction. Fig. 3 is a similar view of one of the upper body sections of the same. Fig. 4 is a fragmentary sectional elevation, on an enlarged scale, showing the means for supporting the reinforcing bars preparatory to embedding them in the concrete mass.

Similar characters of reference refer to like parts throughout the several views.

In its general construction, this floor and ceiling construction for buildings comprises a porous body which is made up of a plurality of lower and upper sections, an upper filling consisting principally of a mass of concrete or other coalescent material extending over the upper side of this body and a lower finish applied to the underside of this body.

Each of the lower sections of the body is preferably constructed of L-shape and comprises a lower horizontal rectangular plate 1 and a vertical flange 2 rising from said plate at one edge thereof while the remaining edges are unflanged. Each of the upper sections of the body is also preferably constructed of L-shape and comprises an upper horizontal rectangular plate 3 and a vertical flange 4 depending from one of the edges of this plate while the remaining edges thereof are unflanged. These body sections may be constructed of any suitable material but preferably are made of a mixture of plaster of Paris or gypsum and wood fiber or excelsior, so that they are porous, light and durable and permit of driving a nail or similar fastening through the same without cracking or injuring the material. The length of the upper body section from its flanged to its opposite unflanged edge is less than the measurement of the lower body section from its flanged to its opposite unflanged edge. In assembling a plurality of such body sections, the flanged edge of the plate of each lower section engages with that edge of an adjacent lower body section opposite the flange of the latter, so that the undersides of the several plates of these body sections are flush and form a practically flat, continuous surface. For the purpose of holding the plates of the several lower body sections in alinement with each other, means are provided for interlocking the same. These interlocking means may be varied and as shown in Fig. 1 the same may consist of an inclined shoulder or ledge 5 arranged on the flanged edge of each lower plate and formed by the lower part of a V-shaped groove therein and beveled tongue 6 arranged at the opposite edge thereof, so that when the several lower body sections are assembled, the tongue of each plate engages with the lower side 5 of the groove in an adjacent lower plate and thereby holds the several plates against vertical displacement relatively to each other.

Each upper body section rests with the lower edge of its vertical flange on the upper side of one of the lower plates at a distance from that edge of the latter opposite to its flange, while that edge of the upper body section opposite its flange rests on top of the flange of the companion lower body section to which latter the same may be secured by means of nails 8 or other means.

When a plurality of body sections are thus assembled end to end and side to side, a hollow air space 9 is formed between the superposed sections of a set or pair of body sections which not only produces a light structure but also keeps the same dry and sound-proof.

Owing to the vertical flange of each upper body section being arranged at a distance from the adjacent unflanged edge of the plate of the companion lower body section, a channel 10 is produced between the vertical flanges of the body sections of one set of sections and the vertical flanges of the lower body sections of an adjacent set of sections, which channel opens upwardly but is closed at its bottom or underside by the unflanged edge portions of the adjacent lower body plates, as clearly shown in Fig. 1.

1. When assembling a plurality of such body sections, the same are temporarily supported upon a shoring or support which preferably comprises a plurality of head boards or planks 11 engaging with the underside of the lower body plates and extending across the joints between the same and a plurality of posts or uprights 12 extending from these head pieces to the floor or ground of the building. The lower body plates are preferably temporarily secured to these head pieces by nails 13 passing downwardly through the unflanged edge portions of the lower body plates within the channels 10 and into the head pieces of the shoring, as shown in Fig. 1.

After the body of the floor and ceiling construction has been thus assembled, the floor filling or surfacing is applied to the upper side of the same, which filling preferably consists of a mass of concrete or similar material and is applied to the upper sides of this body in a plastic state so as to completely fill the channels and also extend over the upper side of the upper body plates, and thereby form a horizontal flat floor slab 14 resting upon the upper body sections and provided at intervals on its underside with concrete ribs or beams 15 which are integral with the floor slab and project downwardly into the channels of the body.

These ribs or beams may be reinforced so as to strengthen the same by placing in these channels a plurality of longitudinal reinforcing bars or rods 16 of steel or similar material, which bars become embedded in the concrete beams when filling the concrete into the same and effectively reinforce these beams and the slab above the same when the concrete has become set, seasoned and dry.

After the concrete has thoroughly set and dried, the shoring is removed and the lower ends of the nails 13, whereby the lower body plates are secured to the head pieces

of the shoring, are either cut off or bent upwardly and clenched against the underside of the respective body plates, as shown at the left end of Fig. 1. The underside or ceiling of the building construction for certain purposes is now complete and forms a straight, flat or even surface, which does not require any further finish if the purpose for which the building is to be used does not require it. If, however, it is desired to have a finished appearance of the ceiling, the underside of the lower body plates may be covered by a finish coating or surfacing of plaster or similar material which can be applied to the lower body plates without the use of any lathing or similar means for retaining the plaster on these body plates.

It has been found in practice that when wet concrete or other coalescent material is applied directly to the surface of the porous body sections that the latter are liable to absorb such an amount of moisture or water from the concrete before it has set as to weaken the same. To avoid this, undue suction effect of the body sections, the same are covered on those sides which face the plastic masses with a protecting coating, such as paper or a waterproof material or solution which has the capacity of preventing undue absorption of the moisture therein which otherwise tends to destroy the proper proportion of ingredients in the mixture and weaken the same before it is dry and hard. Such a protecting sheet is shown at 30 between the upper external surfaces of the body sections and the mass of concrete forming the slab and ribs, and at 31 between the lower external surfaces of the body sections and the plaster finish 22 forming the ceiling. By this means weakening of the concrete or plaster is prevented and the same is permitted to dry out naturally and retain its full strength.

For the purpose of causing the floor slab and ribs of the concrete mass when hard to reliably support the body sections and ceiling finish applied thereto, each of the channels between adjacent body sections is so formed that when the concrete ribs are formed therein an interlock between the ribs and body sections is produced which prevents vertical displacement of these members relatively to one another. This is preferably accomplished by providing the lower parts of the opposing surface of the vertical flanges of adjacent body sections with downwardly diverging faces 32, 34 and the upper parts of the same with upwardly diverging faces 33, 35, whereby each channel is contracted between its top and bottom parts. As shown in Figs. 1 and 3 the lower face 32 is of inclined form on the lower external side of the vertical flange of the upper body section and the corresponding upper face 33 is of inclined form on the

upper part of this flange, and the lower face 34 is formed by the inclined upper part of the V-shaped groove at the lower end of the exterior of the vertical flange of the 5 lower body section and the corresponding upper face 35 is of inclined form on the upper part of the exterior of the last mentioned flange. It follows from this that when the plastic concrete mass is poured into 10 a channel that a downwardly enlarged dovetail or key 36 is formed at the lower end of the rib or beam which serves, when dry and hard to sustain the body sections against 15 downwardly movement and securely interlocks these members against displacement.

In order to permit of conveniently locating and supporting the reinforcing bars or rods in their proper position within the 20 channels preparatory to introducing the concrete in the same around said bars, supporting means are provided which are preferably constructed as follows:

Mounted on the bottom of each channel are a plurality of supports each of which 25 comprises a pair of horizontal feet 37 which are preferably embedded in the unflanged edge of the horizontal plate of the adjacent lower body section, 38, 38 two upright legs rising from these feet above the upper side 30 of this plate and a cross bar 39 connecting the upper ends of these legs and preferably of crimped form so as to produce a plurality of upwardly facing seats. Each of these supports or benches is preferably constructed 35 of a single piece of wire those parts of which are outside of the body section may be bent flatwise against the body plate for convenience in shipping these sections compactly but which are bent into a position 40 perpendicular to said plate when ready for use. When the several body sections have been thus assembled to form a channel between them and the bar supports are in their normal position one or more reinforcing bars or rods are placed within the 45 channel with its underside resting in corresponding seats of the supports whereby the reinforcing bars will be located and reliably retained in the proper position while 50 the concrete for the ribs is poured into the channel and around the bars. The upper parts of the bar supports are arranged in the upper enlarged parts of the channels and thus serve as anchors to support the unflanged ends of the horizontal plates of the 55 lower body sections which form the bottoms of the channels when the concrete beams in which these supports or anchors are embedded, have become hard and dry. By this 60 means the erection of the floor and ceiling is facilitated and a stronger and more durable structure is produced.

I claim as my invention:

1. A floor and ceiling construction comprising a plurality of lower L-shaped sections 65

and a plurality of upper L-shaped sections, each lower section having a lower horizontal plate and an upwardly projecting vertical flange which is arranged at one end of the plate and the outer side of which is provided with a horizontal groove on its lower part and a receding inclined face above said groove, and each upper section having an upper horizontal plate which rests at one end on the flange of the lower section while 70 its opposite end is provided with a downwardly projecting vertical flange which is separated by a channel from the flange of the adjacent lower section and the outer side of which is provided with a downwardly inclined lower face and an upwardly inclined upper face, the unflanged end of each lower plate engaging with and supported by the lower part of the groove in the flanged end of the adjacent lower section, the opposing 75 surfaces of the flanges on opposite sides of each channel being narrow between the top and bottom of this channel and enlarging upwardly and downwardly from the narrow part of the channel, and a concrete 80 mass extending over said sections and forming a slab over the upper horizontal plates and depending beams in said channels, each of said beams being contracted between its top and bottom forming laterally projecting 85 anchors at its lower edge upon which the downwardly inclined edges of the vertical flanges of adjacent sections rest.

2. A floor and ceiling construction comprising a plurality of lower L-shaped sections and a plurality of upper L-shaped sections, each lower section having a lower horizontal plate and an upwardly projecting vertical flange which is arranged at one end of the plate and the outer side of which is provided with a horizontal groove on its lower part and a receding inclined face above said groove, and each upper section having an upper horizontal plate which rests at one end on the flange of the lower section while 90 its opposite end is provided with a downwardly projecting vertical flange which is separated by a channel from the flange of the adjacent lower section and the outer side of which is provided with a concrete 95 mass extending over said sections and forming a slab over the upper horizontal plates and depending beams in said channels, each of said beams being contracted between its top and bottom forming laterally projecting anchors at its lower edge upon which the downwardly inclined edges of the vertical flanges of adjacent sections rest.

2. A floor and ceiling construction comprising a plurality of lower L-shaped sections and a plurality of upper L-shaped sections, each lower section having a lower horizontal plate and an upwardly projecting vertical flange which is arranged at one end of the plate and the outer side of which is provided with a horizontal groove on its lower part and a receding inclined face above said groove, and each upper section having an upper horizontal plate which rests at one end on the flange of the lower section while 100 its opposite end is provided with a downwardly projecting vertical flange which is separated by a channel from the flange of the adjacent lower section and the outer side of which is provided with a concrete 105 mass extending over said sections and forming a slab over the upper horizontal plates and depending beams in said channels, each of said beams being contracted between its top and bottom forming laterally projecting anchors at its lower edge upon which the downwardly inclined edges of the vertical flanges of adjacent sections rest.

3. A floor and ceiling construction comprising a plurality of lower L-shaped sections and a plurality of upper L-shaped sections, each lower section having a lower horizontal plate and an upwardly projecting vertical flange which is arranged at one end of the plate and the outer side of which is provided with a horizontal groove on its lower part and a receding inclined face above said groove, and each upper section having an upper horizontal plate which rests at one end on the flange of the lower section while 110 its opposite end is provided with a downwardly projecting vertical flange which is separated by a channel from the flange of the adjacent lower section and the outer side of which is provided with a concrete 115 mass extending over said sections and forming a slab over the upper horizontal plates and depending beams in said channels, each of said beams being contracted between its top and bottom forming laterally projecting anchors at its lower edge upon which the downwardly inclined edges of the vertical flanges of adjacent sections rest.

4. A floor and ceiling construction comprising a plurality of lower L-shaped sections and a plurality of upper L-shaped sections, each lower section having a lower horizontal plate and an upwardly projecting vertical flange which is arranged at one end of the plate and the outer side of which is provided with a horizontal groove on its lower part and a receding inclined face above said groove, and each upper section having an upper horizontal plate which rests at one end on the flange of the lower section while 120 its opposite end is provided with a downwardly projecting vertical flange which is separated by a channel from the flange of the adjacent lower section and the outer side of which is provided with a concrete 125 mass extending over said sections and forming a slab over the upper horizontal plates and depending beams in said channels, each of said beams being contracted between its top and bottom forming laterally projecting anchors at its lower edge upon which the downwardly inclined edges of the vertical flanges of adjacent sections rest.

- projecting anchors at its lower edge upon which the downwardly inclined edges of the vertical flanges of adjacent sections rest, supports arranged in each of said channels and each embedded at its lower end in the adjacent part of the horizontal plate of the respective lower section while its upper part projects into the upwardly enlarging upper part of the respective channel, and reinforcing bars arranged in the upwardly enlarging upper part of said channel and resting on the upper part of said support and embedded with the same in the concrete of said beam.
3. A floor and ceiling construction comprising a plurality of porous body sections arranged adjacent to each other and forming between them a plurality of channels, a plurality of supports arranged in said channels and each having horizontal feet embedded in these portions of said body sections forming the bottom of said channels, legs rising from said feet and a crimped cross bar connecting the upper ends of said legs, reinforcing bars arranged in said channels and resting on said cross bars, and a mass of concrete extending over said sections and into the channels between the same and embedding said reinforcing bars and upper parts of said supports.
4. A floor and ceiling construction comprising a plurality of L-shaped lower sections and a plurality of L-shaped upper sections, each lower section having a comparatively long lower horizontal plate one end of which is provided with an upstanding vertical flange while its other end is unflanged and each of the upper sections having a comparatively short horizontal upper plate one end of which is unflanged and rests on the upper edge of the upstanding flange of one of the lower sections while its opposite end is provided with a depending vertical flange which rests on top of the companion lower plate and is separated from the vertical flange of the adjacent upper section forming a channel therebetween, and an anchor secured at its lower end in that part of each lower plate forming the bottom of a channel and having its upper part projecting upwardly into said channel, whereby upon covering said sections and filling the channels between the same with concrete the anchors will become embedded in the concrete and form a support for the plates of said lower sections.
5. A floor and ceiling construction com-

prising a plurality of L-shaped lower sections and a plurality of L-shaped upper sections, each lower section having a comparatively long lower horizontal plate one end of which is provided with an upstanding flange while its other end is unflanged, and each of the upper sections having a comparatively short horizontal upper plate, one end of which is unflanged and engages the upper edge of the upstanding flange of one of the lower sections while its opposite end is provided with a depending flange which rests on the companion lower plate and is separated from the upstanding flange of the adjacent lower section forming a channel therebetween, and an anchor arranged on that part of each lower plate forming the bottom of a channel, whereby upon covering said sections and filling the channels between the same with concrete the anchors will become interlocked with said concrete and form a support for the plates of said lower sections.

6. A floor and ceiling construction comprising a plurality of L-shaped lower sections and a plurality of L-shaped upper sections, each lower section having a comparatively long lower horizontal plate one end of which is provided with an upstanding flange while its other end is unflanged, and each of the upper sections having a comparatively short horizontal upper plate one end of which is unflanged and engages with the upper edge of the upstanding flange of one of the lower sections while its opposite end is provided with a depending flange which rests on the companion lower plate and is separated from the upstanding flange of the adjacent lower section forming a channel therebetween, the upstanding and depending flanges on opposite sides of each channel having those parts of their opposing faces between their upper and lower ends arranged comparatively close together while the upper and lower parts of said faces are separated farther than the central parts of said faces so that each of said channels enlarges upwardly and downwardly from a point between the top and bottom of said channel, whereby upon covering said sections and filling the channels between the same with concrete said flanges on opposite sides of each channel will become interlocked with the concrete beam between the same against vertical displacement relatively to each other.

JAMES G. DAVIS.
